UNITED STATES PATENT OFFICE.

BENJAMIN DAVIES, OF WEST HOBOKEN, NEW JERSEY, ASSIGNOR TO L. STRAUS & SONS, OF NEW YORK, N. Y.

DESIGN FOR A GLASS VESSEL.

SPECIFICATION forming part of Design No. 24,202, dated April 16, 1895.

Application filed March 20, 1895. Serial No. 542,546. Term of patent 7 years.

To all whom it may concern:

Be it known that I, BENJAMIN DAVIES, a subject of the Queen of Great Britain, and a resident of West Hoboken, in the county of Hudson and State of New Jersey, have invented and produced a new and original Design for Glass Vessels, of which the following is a specification, reference being had to the accompanying drawings, in which—

10 Figure 1 is a plan view of a dish ornamented with my design, and Fig. 2 represents a cross sectional view of the same.

The leading feature of my design consists of leaf-shaped or pointed-oval fields of small squares alternating with substantially circular fields having rosettes, each of the leaf-shaped fields with a rosette each side of and near its base, being inclosed by a substantially dome-shaped outline of curved deep 20 grooves. The general effect of this leading feature is similar to the trefoil or three-leaf clover, with the center leaf elongated and pointed at both ends.

In the design as represented in the accompanying drawings, a large conventional rosette *a* occupies the center of the dish, and eight pairs of deep grooves *b* commence at points diametrically opposite and adjacent to the rosette *a* and extend to the margin of the 30 dish, the point of meeting of each pair of grooves *b* at the margin forming the apex of the leading feature of the design.

Between each pair of grooves *b* are two oppositely curved deep grooves *c* which meet and 35 form points at the same places as the points of meeting of the grooves *b* both at the mar-

gin of the dish and near the rosette *a* where the grooves *b* commence. These grooves *c*, in pairs, form the leaf-shaped or pointed-oval fields which are crossed by smaller grooves 40 forming squares which, in turn, are each crossed by two or more fine grooves.

As the grooves *b* and *c* of the various pairs cross each other, they provide substantially circular fields which are occupied by rosettes 45 *d* alternating with the leaf-shaped fields; and they also provide triangular spaces *g* which are occupied by small sprays of fine grooves. The marginal spaces between the apexes of the figures or the points of meeting of the 50 grooves *b* and *c* are occupied by fan-shaped figures *f*.

The grooves forming the ornamentation of some of the fields and spaces are omitted from some of said fields and spaces, in order to 55 more prominently illustrate the leading feature of the design; but it is to be understood that the fields and spaces unoccupied in the drawings will, in practice, be ornamented by rosettes, cross-fields and sprays duplicates of 60 those shown.

Having thus described my invention, what I claim is—

The design for glass vessels substantially as herein described and shown. 65

In testimony whereof I affix my signature in presence of two subscribing witnesses.

BENJAMIN DAVIES.
